UNITED STATES PATENT OFFICE.

HARRY WEARNE, OF RIXHEIM, GERMANY.

DESIGN FOR WALL-PAPER.

SPECIFICATION forming part of Design No. 33,899, dated January 8, 1901.

Application filed December 18, 1900. Serial No. 40,811. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a section of wall-paper embodying the features of my design.

The leading features of my design consist in a bunch of flowers of the hyacinth variety, a ribbon bow-tie at the stems of the flowers, and ribbon festoons extending from the bow-tie, which festoons appear florally decorated.

The minor features of the design consist in leaves, which apparently separate the flow-

ers in the hyacinth group and in the formation of the bow at the stems, which bow shows loose ends and festooned trailers supporting 20 bouquets of wild roses.

Having thus described my invention, I claim as new and desire to secure by Letters Patent—

The design for wall-paper as herein shown 25 and described.

In testimony whereof I have signed my name to this specification in the presence of two subscribing witnesses.

HARRY WEARNE.
